ELLIS HARTLEY, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS.

BUILDER MECHANISM FOR SPINNING AND LIKE MACHINES.

Application filed May 16, 1925. Serial No. 30,692.

To all whom it may concern:

Be it known that I, ELLIS HARTLEY, a subject of the King of Great Britain, residing at Whitinsville, in the county of Worcester

5 and Commonwealth of Massachusetts, have invented certain new and useful Improvements in Builder Mechanisms for Spinning and like Machines, of which the following is a specification.

10 This invention to be hereinafter described relates to cap spinning machines, and more particularly to the means for locking the builder mechanisms of such machines.

In cap spinning machines as at present 15 constructed, part of the builder mechanism comprises a revolvable shaft with a sleeve slidably mounted thereon and cooperating therewith by means of a spline fixed to the shaft. Rotary motion is imparted to the 20 sleeve by means of a gear fixed to the sleeve and while the bobbins are being filled cooperates with a gear rotatable on a stud fixed to the machine frame and deriving its motion from an adjacent power transmitting 25 mechanism of the machine. Normally the sleeve gear is held in operative position by means of a locking member comprising a latch swingable on a stud fixed to the framing of the machine and cooperating with a 30 groove in the sleeve.

When the bobbins have been filled and are 35 ready to be doffed the operative disengages the latch and slides the sleeve gear from its meshing relation with its driving gear after which by means of a hand wheel attached to the end of the sleeve he turns the shaft so as to properly position the bobbin rails to facilitate the removal of the filled bobbins and the replacement of empty ones.

40 When this is accomplished he pushes the sleeve gear into its normally operative position and sometimes neglects to return the latch to its locking position with the result that the sleeve gear slips from engagement 45 with the driving gear causing a breakage of the yarn and damage to parts of the machine. By means of my invention this objectionable construction is eliminated thus resulting in preventing waste and the avoidance 50 of requirements for repairs.

The novel features of my invention will be

apparent from the following description taken in connection with the drawings:

In the drawings:

Figures 1 and 2 are respectively a front 55 elevation and an end elevation of a portion of a spinning machine with parts broken away and parts omitted to show the relative position of my improvement in the machine. Figure 3 is a section on line 3—3 of Figure 60 2. Figure 4 is an enlarged elevation of my improved locking device.

My invention is herein illustrated as applied to a cap spinning machine having an end frame 10 supporting a stationary 65 spindle rail 11 on which are stationed a plurality of spindles 12 carrying caps 13, and 14 is the bobbin rail carrying the bobbin tubes 15 which are raised and lowered by the motion imparted by the usual type of 70 builder mechanism, which includes a sleeve 16 revolvable in bearing 17 forming a part of bracket 24 fixed to the frame 10. The sleeve 16 is slidably mounted on the builder shaft 18 and revolvable therewith by means 75 of the splines 19 fixed to the sleeve and slideable in ways planed in the shaft.

Rotary motion is imparted to the sleeve and thence to the shaft by a gear 20 fastened to the sleeve and meshing with gear 80 21 which derives its motion from power transmitting means not shown in the drawings. A transverse groove 22 cut in the hub of gear 20 coacts with the locking member 23 slidably mounted in the bracket 24 85 to lock the sleeve in its normally operative position. The locking member is normally maintained in its locking position by a resilient member 25 abutting between a lug 26 on the locking member 23 and the inner 90 flange 27 of the bracket 24. Preferably the resilient member is a coiled wire spring slidably mounted on the stud 28, one end of which is fixed in the bracket flange 27 and the other end loosely passes through a hole 95 in the lug 26. The locking member is slidably held in the bracket 24 by means of the retaining cap 29 fastened to the bracket 24 by the bolt 30 and passing through the slot 31 in the locking member 23.

In the operation of doffing it is necessary to disconnect the power transmitting means

from the builder motion to enable the operative to position the bobbin rail. This he accomplishes by first releasing the locking member 23 from its contact with the groove 22, secondly by sliding the sleeve gear 20 from its meshing contact with the driving gear 21 and thirdly manually rotating the hand wheel 32, fastened to sleeve gear so that motion is communicated to the builder shaft and thence through the usual connections of the ordinary type of builder motions, the bobbin rail is set in proper position. To facilitate the release of the member 23 from its locking relation with the sleeve gear, manually operative means are provided, preferably I use a rack 33 cut or affixed to the back of the locking member 23 and cooperating with a pinion 34 fixed to shaft 35 rotatable in bearings maintained in the bracket 24. By means of a handle 36 fixed to the shaft 35 the operative with one hand readily raises the locking member against the resistance of the compression spring 25 sufficiently high to release it from contact with the groove 22 and with his other hand pulls the sleeve gear out from its meshing contact with the driving gear; the operative then relinquishes his hold on the handle 36 and the lower end of the locking member is forced by the compression spring 25 into contact with the tapered end 37 of the sleeve gear hub.

After the bobbins are doffed and before starting the machine the operative pushes the sleeve gear into engagement with its driving gear, by so doing the locking member by means of the compression spring, automatically snaps into engagement with the groove in the hub of the sleeve gear and the machine may be started without breaking the yarn or damaging the machine.

I claim:

1. The combination with a cap spinning machine having a movable bobbin rail and

mechanism for raising and lowering said rail including a revolvable shaft, of a sleeve revolvable with and slidably mounted on said shaft, a driving gear, a gear fixed to the sleeve in position to engage and disengage said driving gear as the sleeve is slid along the shaft, a transverse groove in the sleeve, a member slidably mounted in a bracket fixed to the framing of the machine and cooperating with said groove to lock the sleeve gear and driving gear in normally operative position, means to normally maintain said member in its locking position and manually operative means to release said member from its locking engagement with said sleeve.

2. The combination with a cap spinning machine having a movable bobbin rail and mechanism for raising and lowering said rail including a revolvable shaft of a sleeve revolvable with and slidably mounted on said shaft, a driving gear, a gear fixed to the sleeve in position to engage and disengage said driving gear as the sleeve is slid along the shaft, a transverse groove in the sleeve, a bracket fixed to the framing of the machine, a locking member slidably mounted in said bracket and adapted to cooperate with the groove in the sleeve to lock the sleeve gear and driving gear in normally operative position, a resilient member cooperative with said bracket and the locking member to normally maintain the locking member in its locking position, a shaft supported in bearings of said bracket, a pinion fixed to said shaft, a rack in a fixed relation with said locking member cooperating with said pinion and a handle on the pinion shaft whereby the locking member may be released from its locking position.

In testimony whereof, I have signed this specification.

ELLIS HARTLEY.
